UNITED STATES PATENT OFFICE.

ERNST PAUL LEHMANN, OF BRANDENBURG, GERMANY.

METHOD OF RIGIDLY SECURING WIRE TO OTHER OBJECTS.

SPECIFICATION forming part of Letters Patent No. 728,118, dated May 12, 1903.

Application filed November 4, 1901. Serial No. 81,063. (No model.)

To all whom it may concern:

Be it known that I, ERNST PAUL LEHMANN, a subject of the King of Prussia, German Emperor, residing at No. 6 Plauerstrasse, Brandenburg-on-the-Havel, Prussia, German Empire, have invented certain new and useful Improvements in Methods of Rigidly Securing Wire to other Objects, (for which I have made application for Letters Patent in Germany, Serial No. L. 15,395, dated April 10, 1901; in France, dated June 7, 1901, and in England, No. 11,605, dated June 6, 1901,) of which the following is a specification.

My invention relates to an improved method of rigidly securing wire—for instance, a shaft, shank, or stem of wire—to other objects—for instance, to parts of a toy or any other articles—and the purpose of this invention is to avoid soldering, welding, sealing, or cementing the wire to such other parts or objects, which may consist of sheet metal or any other material, such as porcelain, cast-iron, lead, &c.

This new and improved method of rigidly securing wire to other objects consists in flattening or deforming one or more portions of the wire and in lodging the same within apertures of different shape provided within the said parts or objects or within apertures of the like shape arranged in different positions, as will be hereinafter more fully described.

The accompanying drawings, illustrating several forms as examples, are intended to make my invention well understood.

In the said drawings, Figure 1 illustrates a piece of wire flattened at one portion of its length, the flattened portion being seen in side elevation. Fig. 2 represents the same portion of wire with the flattened portion seen in plan view. Fig. 3 illustrates a piece of wire flattened at two portions of its length, the intermediate portion retaining its original shape or cross-section. Fig. 4 is a plan to Fig. 3. Fig. 5 illustrates the mode of rigidly securing the wire, as shown in Fig. 1, within a fan or other article of sheet metal, the wire being shown lodged within the apertures of the two sides of sheet metal before finally securing it in position. Fig. 6 represents the same figure as Fig. 5, with the wire finally and rigidly secured within the sides of the metal fan. Fig. 7 illustrates the mode

of securing the wire, shaped as shown in Figs. 1 and 2, within the two sides of a sheet-metal wheel, the wire being shown lodged within the apertures of the two sides of metal before being finally secured in position. Fig. 8 is a side view of Fig. 5. Fig. 9 is a sectional view of the sheet-metal wheel corresponding to Fig. 7, with the wire finally secured in position. Fig. 10 is a side elevation of the wheel according to Fig. 9. Fig. 11 shows the shape of the aperture in one of the wheel sides for lodging the wire. Fig. 12 illustrates the shape of the aperture in one of the wheel sides, with the end of the wire placed across the slit according to one modification of my invention. Fig. 13 is a sectional elevation representing another modification of rigidly securing the wire to an article of sheet metal. Fig. 14 is a sectional elevation representing a further modification of rigidly securing the wire to an article of sheet metal, such as a wheel. Fig. 15 is a sectional elevation representing another modification of this invention. Fig. 16 illustrates the shape of the aperture in one of the sides of the object to be secured to the wire. Fig. 17 illustrates the shape of the aperture in the other side of the object to be secured to the wire. Fig. 18 is a side elevation of a wire lodged in one half side of a handle, illustrating another modification of my invention. Fig. 19 is a side elevation of a wire lodged within both jointed half parts of the handle, according to the same modification. Fig. 20 represents the two half parts of the said handle jointed to each other, seen against the end of said handle; and Fig. 21 represents the two half parts of said handle separate from each other and seen against the opposite side or shaft end of the said handle.

Referring to Figs. 1 and 2, *a* is a piece of wire of any convenient length and preferably of circular cross-section, which will be supposed to be adopted throughout the other modifications and figures of the drawings, though the cross-section of the wire might be polygonal, oval, angular, or square without changing the material features of this invention. As clearly shown in Fig. 1, the flattened portion *b* of the wire *a* exceeds in width the original diameter or cross-section of the wire *a*. The end of the wire, as at *c*, at first retains the original cross-section.

For securing the wire *a* within the sides *d* and *e* of a fan or other object, as shown in Fig. 5, one of the said sides—say *e*—is provided with an aperture of the shape represented in Fig. 11, allowing the passage of both the original cross-section of the wire and of its portion *b*, extended in width, as before described. The other side of the fan—say *d*—is provided with an aperture corresponding to the original cross-section of the wire—say of circular shape—as seen in Fig. 8. The wire is introduced into the two sides *e* and *d* from the side *e*, and the end *c* projects through the side *d*. The flattened portion *b* of the wire is prevented from turning within the slot of the side *e*, and the same flat portion *b* of the wire cannot proceed through the round aperture of the side *d*. According to Fig. 5, the wire could nevertheless be withdrawn as it has been introduced. To prevent such sliding back, the projecting end *c* of the wire is subjected to a flattening operation after the wire has been introduced into position. The flattened portion *c'*, (shown in Fig. 6,) exceeding in width the original cross-section of the wire, prevents sliding back of the wire *a* through the aperture in the side *d*, and consequently the wire is rigidly lodged within the two sides *d* and *e*.

Figs. 7, 8, 9, and 10 illustrate the same method of securing a wire shaft *a* within the two sides *d* or *e* or hub portions of a sheet-metal wheel. The hub portion *e* of one side of the wheel is provided with an aperture of the shape illustrated by Fig. 11, and the hub portion *d* of the other side of the wheel with a round hole, as shown in Fig. 8. The wire, prepared and shaped as shown in Figs. 1 and 2, is introduced from the side *e*, its round end *c* projecting from the aperture in the hub *d*, as shown in Figs. 7 and 8, after which the projecting end *c* is subjected to a flattening operation extending the width of the flattened end *c'* beyond the original diameter of the wire. The flattened portion *c'* cannot be withdrawn from the round hole in the hub portion *d* and the wire is prevented from turning within the slotted portion of the hub *e*. The flattened portion *b* cannot be pushed forward through the round hole in the hub *d*, and consequently the wire is rigidly secured in the wheel, as illustrated by Figs. 9 and 10.

Another modification of this invention consists in forming the wire at once with two flattened portions *b* and *c'*, as shown in Figs. 3 and 4, the intermediate portion *f* between the two flat portions *b* and *c'* having the original diameter and shape of the wire *a*. To secure a wire prepared in this manner into the two sides or halves of a wheel or other article, the said two sides must be separate. The aperture in each of the two hubs *d* and *e* is exactly alike, as shown in Fig. 11. The wire *a* is introduced into the said hubs from the side of the hub *e*, as shown in Fig. 9, the flattened end *c'* projecting from the hub *d*. Then the one half of the wheel carrying the

hub *d* engaging the intermediate portion *f* of the wire *a* is turned through an angle of ninety degrees, thus placing the flat portion *c'* across the slot of the hub, as shown in Fig. 12. The two halves of the wheel keeping this position are secured to each other by soldering or by mechanical means, and the shaft *a* is rigidly lodged between the two sides and prevented from turning around its longitudinal axis.

Another modification of this invention consists in deforming or flattening the wire *a* at only one portion of its length, the flattened portion being located either at the end of the wire, as shown in Figs. 13 and 15, or at an intermediate portion, as at *b*, Fig. 14.

Referring to Fig. 13, the end of the wire shaft *a* is rigidly secured within the side *h* of an article in the following manner: The said side *h*, of sheet metal or any other material, is provided with a narrow slot, as shown by Fig. 16. A disk, cap, or plate *k*, having a round hole, as illustrated by Fig. 17, is placed against said slotted side *h*, and the said plate or disk *k* may be connected to a similar guide-plate *i*, which, however, forms no part of this invention and might as well be omitted. The guide-plate has a round hole similar to that in the disk *k*. The shaft *a*, having its end flattened, as at *g*, is first passed with its round stem through the hole of the plate or disk *k* and through the corresponding hole of the guide-plate *i*, if such be employed. The projecting flat end *g* then is introduced into the slit provided in the side *h*, after which the said plate or disk *k* is rigidly secured to the side *h* by soldering or by mechanical means. It will be easily seen that the round portion or original cross-section of the wire *a* cannot pass the slit within the side *h* and that the flattened portion *g* of the wire *a* cannot return through the round hole within the disk or plate *k*. At the same time the wire is prevented from turning owing to the flat portion *g* being lodged within the slit or plate *h*, and consequently the shaft *a* is rigidly secured within the side *h*.

The modification illustrated in Fig. 15 is substantially of the same kind. The shaft *a* is desired to be rigidly secured within the plate *h*, which is provided with a round hole, as shown in Fig. 17. When the said shaft *a* has been introduced with its round shank into the hole of plate *h*, the plate or disk *k*, provided with a slit, as shown in Fig. 16, is shifted over the flattened portion *g* of the wire *a*, and the disk or plate *k* is then rigidly secured to the plate *h* by soldering or other means. The flat portion *g* of the shaft *a* prevents the latter from being withdrawn toward the side of the plate *h*, and the round portion of the wire prevents the shaft *a* from being withdrawn toward the side of the plate *k*. The shaft *a* cannot be turned around its longitudinal axis owing to the flat portion *g* being lodged within the slit of plate *k*. The shaft, therefore, is again rigidly secured.

In all the modifications before described it will be seen that two bearings are employed and necessary for rigidly securing the wire. In Fig. 14 I have shown another modification 5 in which three bearings are provided and the shaft *a* has only one flattened portion, as at *b*. To perform this mode of rigidly securing the wire, the wheel or other object is again made of two parts separate from each other 10 before the wire has been lodged in position.

To one of the two sides of the wheel—say to the inside of the hub *d*—a cup-shaped cap *m* or bearing-plate is rigidly secured. The said cap *m* is provided with an aperture of the 15 shape represented in Fig. 11. The hub portions *d* and *e* of the two wheel sides have circular holes, such as shown in Figs. 8 and 17. The wheel side carrying the hub *e* is first slipped onto the round portion of the shaft 20 *a*. Then the flattened portion *b* of the wire is slipped into the aperture of the cap *m*, the round end *c* of the wire *a* projecting from the round hole of the hub *d*, after which the two halves of the wheel are rigidly secured to each 25 other by soldering or mechanical means. It will be seen that the flattened portion *b* of the wire is prevented from being shifted forward and backward by the round holes of the two hub portions *d* and *e* and that turning 30 of the wire is prevented by the flat portion *b*, lodged within the bearing of the cap *m*. The wire *a* again is rigidly secured.

In the modification illustrated by Figs. 18 to 21 the wire shaft *a* is intended to be rigidly secured to a handle consisting of two separate half parts *r* and *s*. At one end the said half parts *r* and *s* have a lug *t*, with a slit traversing said lugs, and at the other end of said half parts a semicircular open bearing *u* is provided. The shaft *a* in this case is previously formed with two flat or deformed portions, as at *b* and *c'*, such as shown in Figs. 3 and 4. The flat end *c'* is first introduced into the slit of the lug *t* of one half 45 part *r*, as shown in Fig. 18, the round shaft being sunk into the open bearing *u*. Then the other half part *s* is slipped, with its slotted lug *t*, over the projecting free end *c'* of the wire *a*, the two lugs *t* of the two half parts *r* and 50 *s* overlapping each other, as shown Fig. 20. The bearing *u* of the half part *s* engages the round part of the shaft *a* opposite the bearing *u* of the other half part *r*. When the other part *s* is in place, as shown in Fig. 19, the 55 two halves *r* and *s* are rigidly secured to each other by any suitable means—for instance, by bending the projecting metal tongues *v* of one side *r* down to clasp the edge of the counter side *s*—and the shaft *a* is rigidly secured with- 60 out soldering, sealing, or cementing the same between the two half parts *r* and *s*, the round portion *f* preventing the shaft from being shifted through the slits of the lugs *t* and the flat or deformed portion *b* preventing the 65 shaft from being shifted toward the side of the bearings *u*. Instead of providing the two halves *r* and *s* with lugs *t*, traversed by slits,

as shown, a slit-shaped bearing for the flat end *c'* of the wire may be formed in the same manner as the round bearing *u*—viz., by 70 forming in one lug *t* an open bearing into which the flat end *c'* is laid and making the other lug *t* fit closely to the flat end *c'*, thus engaging the said flat end *c'* between the two lugs *t*, which subsequently are joined to each 75 other in any convenient manner—for instance, by metal tongues, same as *v*.

In lodging the shaft *a* between two or more parts, such as *r* and *s*, which are separate in the direction of the axis or length of the 80 shaft, instead of providing two separate flat portions, such as *b* and *c'*, on the shaft *a* a single flat portion might be employed. In this case a stop, collar, pin, or projecting part is secured to the wire *a*, as at *w*, Figs. 85 18 and 19, or such stop may be formed by the plate or casing into which the shaft enters. It will be seen that on providing a stop of this kind, located as at *w*, the handle cannot be pushed forward nor backward on the shaft 90 *a*, the forward motion being prevented by the said stop *w*, the backward motion by the impossibility of making the round bearing *u* slide over the flat portion *b* of the wire. In such case the two flat portions *b* and *c'* may 95 be made in one.

Having now particularly described and ascertained the nature of my said invention and in what manner the same is to be performed, I declare that what I claim is—

100

1. The method of rigidly securing wire to other objects, consisting in flattening or deforming the original cross-section of the wire at one or more portions of its length, and lodging the same within two or more bearing-apertures of non-registering contour, substantially as and for the purpose described.

2. The method of rigidly securing wire to other objects, consisting in previously providing the wire with a flattened or deformed portion at an intermediate part of its length, introducing the wire into two bearing-apertures of non-registering contour, and subsequently flattening or deforming the wire at another portion of its length, substantially as and for the purpose described.

3. The method of rigidly securing wire to other objects, consisting in previously providing the wire with flattened or deformed portions, introducing the wire into two bearing-apertures of substantially the same contour provided in separate parts of the object, changing the position of one of the two apertures by turning one of the two separate parts of the object so that the contour of the apertures will not coincide, and finally, securing the two separate parts of the object to each other in their changed position, substantially as and for the purpose described.

4. The method of rigidly securing wire to other objects, consisting in flattening or deforming the wire near one of its ends, lodging the flattened or deformed portion within a slot preventing the wire from being turned,

passing the original portion of the wire through a corresponding aperture of a plate, disk or cap, and finally securing said plate, disk or cap to the piece having the slotted bearing portion, substantially as and for the purpose described.

5. The method of rigidly securing wire to other objects, consisting in flattening or deforming the wire near one of its ends, lodging the original portion of the wire within a bearing-aperture of the object to be secured, passing a slotted portion over the flattened or deformed end of the wire to engage the said end within the said slot, and, finally, securing the 15 said slotted portion to the portion carrying the other bearing, substantially as and for the purpose described.

6. The method of rigidly securing wire to other objects, consisting in previously providing the wire with a flattened or deformed portion at an intermediate part of its length, lodging the wire within a plurality of bearing-apertures provided in separate parts of the object to be secured, of which apertures a

portion corresponds to the original cross- 25 section of the wire and a portion to the flattened or deformed portion, and finally securing the separate parts to each other, substantially as and for the purpose described.

7. The method of rigidly securing wire to other objects, consisting in previously providing the wire with flattened or deformed portions intermediate its length, and lodging the same between two separate half parts of the object to be secured, by passing the flattened 30 or deformed end of the wire through corresponding apertures provided in the two parts, engaging the round or original portion of the wire within corresponding semicircular bearings of the two half parts, and finally securing the said half parts to each other, substantially as and for the purpose described. 35

In witness whereof I have hereunto set my hand in presence of two witnesses.

ERNST PAUL LEHMANN.
